United States Patent

Des. 237,336
Patented Oct. 28, 1975

237,336

TABLE

Dominick Loscalzo, Whitestone, and Howard W. Michaelson, Coram, N.Y., assignors to A-Bee Syndicate, Inc., New York, N.Y.

Filed Dec. 29, 1972, Ser. No. 319,690

Term of patent 14 years

Int. Cl. D6—03

U.S. Cl. D6—176

FIG. 1.

FIG. 5.

FIG. 3.

FIG. 4.

FIG. 1 is a top plan view of a table showing our new design;
FIG. 2 is a sectional view taken through line 2—2 of FIG. 1;

FIG. 3 is an elevational view thereof;
FIG. 4 is a bottom plan view thereof; and

FIG. 5 is a perspective view thereof.

We claim:

The ornamental design for a table, substantially as shown.
